UNITED STATES PATENT OFFICE

GEORGE GODDU, OF WINCHESTER, MASSACHUSETTS, ASSIGNOR TO UNITED SHOE MANUFACTURING CORPORATION, OF PATERSON, NEW JERSEY, A CORPORATION OF NEW JERSEY

FASTENING INSERTING MACHINE

Application filed January 24, 1927. Serial No. 163,080.

My invention relates to machines for inserting fastenings in such work as the bottoms of shoes, the particular embodiment of the invention herein illustrated being adapted for securing the toe-portion of an outsole of the McKay type of shoe to the insole and upper. When the toes of McKay shoes have abrupt changes in contour, as when they are sharply pointed or are square, it is not practicable to carry the outsole-stitching about them. Instead it is customary to secure this portion by a series of successively driven fastenings at the time the outsole is laid, and then stitch around the remainder of the sole. By this practice, several difficulties are introduced. Since a number of fastenings must be used, a considerable time is consumed in their separate insertion, and they may not be most advantageously located with respect to each other and to the edge of the sole. The work is held in the hands of the operator, and since the way in which the fastenings clinch depends upon the pressure, this clinch and consequently the manner in which the outsole and upper are drawn together may not be uniform, and are almost certain to differ from the stitcher in effect. An uneven crease results. This is increased by differences in curvature of the tread-surface of the sole or irregularities in the bottom of the channel, which further disturb the uniformity of clinching. An object of the invention is to provide for the rapid insertion of the fastenings, uniformly positioned and clinched.

As a feature of the invention leading to the attainment of this object, I employ a novel organization in which there are a plurality of supports or operating sections, in each of which a tool, such as a reciprocatory fastening-inserting driver, is movable. The supports are arranged to yield under the influence of the work in the direction of movement of the tool, or that in which said work is moved by a jack, upon which it is carried against abutment-surfaces upon the supports. In the utilization previously mentioned, the surface of the work with which the supports contact is upon the shoe-bottom, and the yield gives a substantially uniform clinching ef-

fect, regardless of surface-irregularities. Therefore, the elements secured are held together with approximately equal force throughout the series of fastenings, producing an even crease, and since the tools act simultaneously in all the supports the operating time is short. I prefer also to locate the inserting or operating points definitely upon the work, as with respect to the edge of the sole operated upon. To this end, the supports are made yieldable in another direction, or transversely of the previously mentioned yield, their relation being determined by the contact of gage-surfaces with the work. As one way of arranging for these movements of the driver-support, it may be yieldable upon a carrier, which, in turn, is movable, upon a universal joint, on the frame of the machine.

As another feature of the invention, a substantially uniform inserting force is provided in connection with all the inserting tools or drivers, whatever may be their position as a result of the yield under the influence of the work. This is accomplished in a novel manner by furnishing a spring for actuating each driver, which may be secured to the frame of the machine or some member common to all the drivers and so arranged as to in no way interfere with the movement of the support, either in its yield longitudinally of the driver or about its universal joint, the preferred connection being through a lever fulcrumed upon the frame for each spring, to which lever the corresponding driver is joined by a link. There is a movable member which simultaneously tensions the springs, together with means which releases the springs for action. Herein is shown as the tensioning means a reciprocatory member carrying a group of pawls, one acting upon each driver. Associated with each pawl is a contact member, which causes it to release its driver.

At the time of clinching a tack or other fastening, the resistance to driving increases over that required for the previous inserting action, tending to separate the abutment-surfaces between which the work is clamped. In apparatus of the character of that herein described, in which one of the abutment-sur-

faces is yieldable, this separation may be sufficient to produce an imperfect clinch. As a feature of the invention, I guard against this by a new combination of elements in which the inserting member is caused to increase the pressure of the abutment member upon the work, as by its movement into engagement with said abutment member. In the present embodiment of the invention, a yieldable driver-support has a contact-surface, which is struck by a surface upon the driver reciprocating in the support to force said support toward the work just as the driver-stroke is being completed. At this time, the support is carried forward slightly by the driver, increasing the clamping pressure as the greatest resistance to driving is encountered.

A further feature of the invention involves members which connect the independently movable fastening-inserting sections in a novel manner, and which determine the spacing between them during their independent movement. In this way, the sections may be allowed to move in adjusting themselves to the work without disturbing the uniform arrangement of the fastenings. At least a portion of the force against which the sections yield outwardly may be exerted through these connecting members, there being associated with them means tending to draw the sections together. There are illustrated links pivotally connecting the sections, with springs exerting their tension upon the terminal links. I have shown one of the sections, as that at the rear of the machine or at the end of the toe of the shoe operated on, as normally fixed, this providing a locating means for the work as it is introduced. The side sections are joined to this fixed section in two series, each connected and tensioned as just indicated.

If the work-portions, as the sole-edges, were required to separate and thus position the inserting sections, they might, especially if thin, be distorted by the force which they must exert. This, in the toes of McKay shoes, would lead to an uneven crease. An additional feature of my invention guards against this, it including a member movable into contact with the tool-supporting sections to effect their separation in preparation for their engagement with the work. This member is preferably a templet having a contour approximately that of the work. It moves the supports beyond their operating positions, and then releases them so they may assume such positions. In this way, the pressure upon the work is only that caused by the force which holds the supporting sections in place against it. The positioning action of the templet is preferably under the power of the machine, while the release may be governed by the operator, as in starting an operating cycle. An effective way of controlling

the templet utilizes a lever having relatively movable arms, by one of which the templet is carried, while the other receives the actuating force. The arms may be connected to move together, causing the templet to separate the supports, or the templet-carrying arm may be freed from the connection to permit the supports to take their operating positions. Preferably, a positive means re-establishes the control of the positioning member or templet by the power means which moves it, this, in the present instance, being by restoration of the connection between the lever-arms effected under the power of the machine.

Under some conditions, as with wide shoes, the distance through which the end inserting sections must be moved from their closest approach is considerable, and the positioning member or templet which moves a plurality of the sections at one time may encounter a considerable resistance. Therefore, as still another feature of the invention, I have furnished for use, if desired, independent means for moving a portion of the plural sections. This means I prefer to arrange for manipulation by the operator, who may, if the character of the work requires, adjust certain sections, as those at the ends just mentioned, thus preparing the machine for smoother operation under power.

A further feature of the invention has to do with the prevention of the inserting operation before the work is properly located. Combined with the inserting mechanism and its actuating mechanism is a movable work-gage, which exercises control over the actuating mechanism. This control may be through connections between the gage and actuating mechanism. The gage movement is produced only when the work has reached the desired position. Until such time, the inserting mechanism will remain disconnected from the actuating mechanism, and therefore inactive. The gage is shown as a back stop mounted upon a slide, which normally locks starting connections for the actuating mechanism, until engagement of the work with the back stop moves the slide to free the connections.

A particular embodiment of the invention is illustrated in the accompanying drawings, in which

Fig. 1 shows a side elevation of my improved fastening-inserting machine, with parts broken away;

Fig. 10, a perspective view of the connection between the tack-drum and its driving mechanism.

A column 10 has secured at its top a head 12, upon the upper face of which is mounted a generally semi-circular bracket 14, with its open side at the front of the machine. Upon this bracket are carried the tack-driving and inserting sections I, of which nine are here shown, though more or less may be employed in accordance with the requirements of the work. Arranged about a forwardly extending shelf upon the bracket, and separated from each other to correspond to the spacing of the tacks as driven in the work, are depressions 16 (Fig. 6), each furnishing the lower half of a socket for a universal joint, the upper section of which is provided by a cap 18 bolted upon the top of the bracket-shelf. Considering now a single inserting section, the socket contains a ball 20, depending from which is a short bearing or carrier-sleeve 22. This sleeve passes through an opening at the bottom of the socket, projecting at the under side of the shelf. Arranged to slide through the sleeve is a tubular portion 24 of a driver-support or holder and work-engaging or abutment member 26 (Fig. 3). Between the top of the body of the support and a washer 28 bearing against the end of the sleeve 22 is a helical spring 30 surrounding the portion 24. The effect of this spring is to hold the member 26 yieldably in its lowest position to receive the pressure of the work which is raised against it upon a jack 31, the form and operating movement of which will be hereinafter described. The downward movement of the support is limited by a split sleeve 32 threaded upon its upper end and having a curved skirt 33 arranged to engage the exterior of the cap 18. By properly positioning these sleeves 32 upon the supports, the position of the latter may be made uniform with respect to the supporting surface of the jack or to the work thereon. Each sleeve may be clamped in its adjusted position by a screw 35 which draws the sections together. At the bottom of a downward extension 34 from the body of each support is an abutment-surface 36 (Fig. 9) for contact with the work, and in this surface is an opening 38 furnishing a nozzle through

which tacks are driven. At the outer side of the opening is a gage member 40 adapted to contact with a sole-edge and thereby locate the nozzle at the desired point in the work. Its distance from the opening may be varied to correspondingly change the spacing of the tacks from the edge, it being guided by slot-and-screw connections 42 upon the support and adjusted by a screw 44.

Movable within the tubular portion 24 of the body of the support is a driver-rod 46 having clamped in its lower divided end a driver 48. A clamping collar 50, which maintains the driver in the split end of the rod, may have a flattened portion moving over a surface 52 upon the support-extension 34, and thus resisting the tendency of the driver-clamp to turn. The driver is shown as guided in the extension, its end entering a passage 54 which terminates in a split retaining quill 56. Tacks T are delivered for driving within this quill through a support-passage 58 and a tube 60 entering the passage from a distributing mechanism D mounted on a cap-piece 61 of the frame. The extent of driving movement of the rod 46 is limited by a threaded collar 62 (Fig. 3) adjustably clamped upon its upper threaded extremity. This collar carries on its under face a cushion 64, which may be of leather, contacting with the upper side of the support-collar 32. In a socket formed at the upper extremity of the driver-rod is seated the end of a strut or link 66, which enters a socket in a lever 68 fulcrumed upon an arm 70 projecting from the bracket 14. Fixed in the arm is one end of a torsion-spring 72, the free end of which presses against the lever 68 above the driver-strut. This spring 72 exerts a constant tendency to force the rod 46 down until the cushion 64 contacts with the support sleeve 32, at which time the driver acts to insert in the work the tack held in the quill 56.

To tension the spring 72 in preparation for the inserting stroke of the driver, and then to release it for such stroke, the following mechanism is preferably employed. At the inner side of the collar 62 is a projection 74 provided with a shoulder 75 for engagement by a pawl 76 pivoted upon an actuating plate 78 and urged toward the projection by a spring-plunger 79. The plate 78 is secured to the lower extremity of a bar 80 guided for vertical reciprocation in the cap-piece 61. Upon the plate is carried one of the pawls for actuating each of the drivers of the series. The shoulder 75 upon each collar is guided laterally during travel of the projection 74 between upstanding walls 84, 84 bolted to the support-collar 32 at opposite sides of a rib 85 therefrom (Fig. 5). Engagement of the walls 84 with the pawl limits the angular movement of the support about its longitudinal axis. The bar 80 receives its reciprocation through a link 86, which joins it to a

bell-crank lever 88 fulcrumed upon the head 12 and having a roll entering a groove 90 in a cam member. This member is fast upon a shaft 92 journaled in the head and driven through non-repeating clutch mechanism 94 by belt-gearing from a counter-shaft 98 rotatable in the foot of the column. Engagement of the clutch may be controlled by a treadle 100 and a connecting-rod 102, the latter being normally depressed by a spring 104 to render the mechanism inactive. The normal or resting position of the plate 78 is as illustrated in Fig. 3. At this time, the drivers have been raised by the pawls 76, so the springs 72 are under tension and the drivers are ready for the inserting stroke. Upon the depression of the treadle and consequent rotation of the shaft 92, the plate 78 rises to an extent sufficient to bring horizontal projections from the pawls into engagement with the lower ends of contact-screws 106 threaded through the frame. This causes the pawls to be swung inwardly upon their pivots, removing them from beneath the shoulders 75 on the driver-rod projections. The drivers, thus released, are forced sharply down by the springs through the supports to effect the insertion of the tacks which are resting within the quills 56. As the drivers approach the end of their strokes, the cushions 64 contact with the upper surfaces of the sleeves 22, so that the supports are forced down slightly, the springs 30 elongating. As a consequence of this, just as the inserting operation is being completed, an additional pressure is put upon the work by the abutment-surfaces 36. This holds it firmly against upward yield, insuring a perfect clinching of the tacks. Upon each holder-extension 34 is a horizontal arm 108, and from each of these arms, save that belonging to the center rear section, depends a stud 110 (Figs. 8 and 9) entering a slot 112 in a horizontal plate 114 secured upon the head 14. The slots converge inwardly, radiating from the vertical axis of the entire series of inserting sections I, and partially guide the sections for movement toward and from the work. The rear section is held against this movement since it is ordinarily desired to insert this tack at the same point for all sizes of shoes. This is accomplished by two studs 115, 115, which project from the arm 108 of this section through holes in the plate 114, which they closely fit. To maintain the nozzles of the sections spaced from each other by the desired distances and to draw them normally toward their position of minimum separation, the adjacent pairs are united by links 116 (Fig. 8) of lengths which will give the chosen relation and which join substantially vertical pins 118 rising from the support-extensions. Forwardly extending links 120 are carried by the pins of the front sections, and to each of these is connected a torsion-spring 122 sur-

rounding a stud 124 at the adjacent end of the plate 114. The springs 122, exerting their effect through the series of links, draw all the sections, except the fixed rear section, inward to a position for co-operation with the smallest work to be nailed. The driver-actuating springs 72, by virtue of the vertical component of their force at the outside of the pivotal points of the supports, also exert some tendency to carry in the lower portions of the supports. Leaf-springs 126, attached to the supports above the links, press these down about the pins to prevent their displacement during the independent upward yield of the supports. 70 75 80

Were the jacked shoe itself depended upon wholly to force out the inserting sections against the springs from their normal position of closest approach to one another to that required for work greater than the smallest size, the pressure of the gages 40 against the sole-edge might distort this and lead to imperfect work. I therefore prefer to effect a preliminary location of the sections, approaching that which would be given by the shoe. For this purpose, there is fulcrumed upon a bracket 128, projecting forwardly from the head 12, a lever having an upper section 130 and an independently movable lower section 132. The section 130 has at the inner edge of its upper extremity a cam-incline 134 acted upon by the edge of the plate 78 as it rises after the inserting operation. A spring 136, connecting an arm 138 of the lever to the bracket, draws the lever-arm 130 into engagement with the plate. Pivoted upon the arm 138 is a horizontally extending latch or connecting member 140 having at 142 a shoulder adapted to engage a tooth 144 upon the side of the lever-section 132 to swing this to the right, as viewed in Fig. 3 of the drawings. A spring 146, joining the latch and bracket 128, holds said latch yieldably against the tooth. An arm 148 upon the lever-section 132 may move into contact with a stop-pin 150, shown as that to which the spring 136 is attached, and limit the amount the tooth 144 can separate from the shoulder 142. Secured to the lever-section 132 by a screw-and-slot connection 152 is a positioning plate or templet 154, which may be adjusted horizontally upon the lever by a screw 156. As is best shown in Fig. 8, this templet is curved to correspond to the toe of a shoe, and may be removed and replaced by other plates in accordance with the form of the particular work being operated on. At its inner end, the latch 140 extends beneath a shoulder 160 upon a vertical bar 162 carried upon a lever 164 fulcrumed upon the frame. 90 95 100 105 110 115 120 125 130

A helical spring 166, connecting the bar 162 and lever 164, acts to draw said bar against the end of the latch 140 to provide for the engagement of the shoulder 160 with the latch-end. The lever 164 is united by a link

168 to the treadle-rod 102 (Fig. 1). When the machine is at rest, the plate 78 occupies the position illustrated in Fig. 3, acting upon the compound lever 130, 132, the sections of which are joined by the latch 140, to carry the edge of the templet against the inner edges of the support-extensions 34, so these are forced back slightly beyond the positions at which their gage-surfaces 40 are to contact with the sole-edge when the work is introduced upon the jack. When the operator depresses the treadle to start the machine, the shoulder 160 draws down the latch 140 against the tension of the spring 146, freeing the tooth 144 from the shoulder 142, and thus leaving the lower section 132 of the lever carrying the templet free. As a result of this, the springs 122 and 72 may now bring the gages against the sole-edge and position the nozzles ready for the insertion of the fastenings. To allow the templet to be reset after an inserting operation, the latch-shoulder 142 must have again come into engagement with the tooth 144 of lever-section 132. If the operator continues to hold down the treadle after tripping the clutch, the position of the bar 162 will prevent this re-engagement. I therefore connect the upper end of the bar to the cam-actuated lever 88 by a slotted link 169. During the final ascent of the bar 80 to its initial position, the inner end of the slot forces out the bar 162, and therefore the latch, until the shoulder 142 engages the tooth, again connecting the lever-sections.

To guard against the actuation of the inserting mechanisms before a shoe is fully in place to receive the fastenings, locking mechanism is provided, this being controlled by the work. The stationary rear section 34 has associated with it a gage or back stop 170, which is guided for movement in the bottom of the section and is mounted pivotally upon a locking slide 172 movable horizontally upon the frame (Figs. 3 and 4). The locking portion of the slide is furnished by a piece 174 secured to the main slide member 172 by a slot-and-screw connection 175, and is capable of adjustment by a screw 176. This adjustment varies the normal position of the back stop when the inner wall of a recess 178 in the contact piece 174 bears against the opposed wall of a recess 180 in a bar 182 guided for vertical movement in the frame. A torsion-spring 184, connected at its ends to the frame and to a depending tail upon the gage, acts both to allow said gage to yield upon its pivot with the work as this is raised by the jack, and also holds the slide 172 in engagement with the bar 182. Formed at the inner face of the bar is a rack 186, with which meshes a gear-segment 188 upon a lever 190 fulcrumed upon the frame and pivotally connected at its opposite end to the bar 162. As long as the ele-

ments are in the relation illustrated in Figs. 3 and 4, the bar 182 is locked against downward movement by the recess in the slide 172, and this, through the connection of the levers 190 and 164, maintains the treadle-rod 102 against movement, and therefore prevents the engagement of the clutch mechanism 94. But when a shoe reaches approximately the operating position upon the jack, the end of the toe contacting with the gage 170 forces the slide 172 in until the bar is freed, this releasing the rod 102 and permitting the treadle 100 to be depressed to start the machine.

As the resistance offered to the templet, in thrusting out from their inmost positions sections at the front of the machine, may be unduly great, an adjustment for these is preferably furnished. Pivoted at opposite sides of the front of the head 12 is a pair of arms 192, 192 geared at 194 to move together (Fig. 8). The pins 110 of the outer sections enter slots 196 in vertically movable slides 198 at the forward extremities of the arms. A spring 200 holds each slide normally raised, it being capable of easy depression to facilitate the separation of these outer sections from the machine. Formed upon one of the arms 192 is an extension 202, at the end of which is mounted a handle 204. This handle is arranged to be turned into clamping engagement with a segment-plate 206, which is fixed upon the frame and through a slot in which a reduced portion of the handle passes. By changing the angle of the extension 202 and securing it by engagement with the segment-plate, the outer sections may be moved in or out to correspond to the width of the shoe being operated upon.

The jack 31 rises from a carriage 208 movable into and out of inserting position upon a table 210. This table is mounted upon the upper extremity of a slide 212 arranged to reciprocate vertically at the front of the column. A vertical adjustment may be given the table upon the slide by a screw and hand-wheel-nut 214. A clamping screw 216 permits jacks of various forms to be readily applied to the carriage. A handle 218 facilitates the movement of the jack between the work-receiving and the fastener-inserting positions. At the bottom, the slide 212 is connected by a link 220 (Fig. 1) to a bell-crank lever 222 fulcrumed upon the column. The lower arm of the lever 222 is joined by a link 224 to a second bell-crank lever 226, the point of connection being variable by means of a slot-and-screw device 228. This allows the extent to which the jack is raised to be altered, correspondingly varying the pressure of the work against the abutment-surfaces 36 of the nozzles. A vertical link 230 extends between the lever 226 and a bell-crank lever 232 fulcrumed upon the head and oscillated by the engagement of a roll which

it carries with a cam-groove 234 in the member rotated by the shaft 92 and also having the groove 90. This mechanism effects the elevation of the jack, with the resulting pressure of the work against the inserting sections and its withdrawal to the normally depressed position.

The distributor D may be of any form suitable for the fastenings employed, for example that disclosed in Letters Patent of the United States No. 1,107,337, McFeely, August 18, 1914. The tack-holding drum 240 of this mechanism, which elevates the tacks for delivery to the tubes 60, may be oscillated from the bar 80 which carries the driver-actuating plate 78. A rack 242 upon the bar (Fig. 3) meshes with a pinion 244 upon a shaft 246 journaled horizontally below the distributor. This, through reducing gearing 248, turns a parallel shaft 250, which has upon it a gear 252 meshing with a segmental gear 254 upon the drum. Since the weight and therefore the momentum of the drum in its oscillation is considerable, I interpose between the shaft 250 and said drum means for absorbing this momentum and thus cushioning the shock produced by the reversal of movement. The gear 252 is loose upon its shaft, and said shaft has, adjacent to the gear, an enlargement 256 (Fig. 10). On the enlargement are fulcrumed opposite three-armed levers 260, 260. Each lever includes an arm 262 substantially parallel to the shaft, upon which arm is a ball working in a socket furnished by a divided block 264 arranged to play in ways 266 extending radially of the gear 252. The other two arms 268 of each lever are curved in opposite directions, the ends of these arms upon both levers normally lying in a common vertical plane. Against these ends a washer 270 surrounding the shaft 250 is forced by a spring 272, the outer end of which abuts against a washer 274 backed by nuts 276 threaded upon the end of the shaft. By a change in the position of these nuts, the force with which the spring presses the washer 270 against the levers 260 may be varied. It will be seen that the shaft 250 drives the drum 240 through the levers 260, and that, as long as the resistance or force exerted by the drum does not exceed that of the spring 272, the levers will not be displaced, and the shaft 250 and gear 252 will move together as a unit. When, however, there is an excessive stress, such as the resistance encountered in reversing the direction of rotation of the drum, this, transmitted through the levers, will turn these and force out the washer 270 against the spring, which will yield so the gear 252 may turn somewhat upon the shaft 250. Injurious shock to the mechanism will therefore be avoided.

Assuming that the toe-portions of the outer soles of shoes are to be nailed to the insoles,

the machine is provided with a jack which will enter properly into the particular sizes of shoes being operated upon and will give, beneath the points of the securing tacks, a clinching surface. A templet 154, approximating in form that of the forward end of the sole, is placed upon the lever-section 132. A shoe S having been placed upon the jack when this is in the position appearing in Fig. 1, it is forced in to the point shown in Fig. 8. Here it finds the gages 40 of the inserting sections I held out of contact with it by the templet, the lever-section 132 being latched in by the member 140. The forward extremity of the sole, however, meets the back stop 170 and forces in its supporting slide 172 to release the treadle. The operator, depressing this, starts the machine upon its inserting cycle by causing the engagement of the clutch 94. The lowering of the treadle releases the latch 140 by the action of the shoulder 160, so that the templet-carrying member 132 is freed to swing away from the inserting sections. Consequently, the side sections are carried in laterally by their springs 122 and 72 until their gages 40 contact with the sole-edge and properly position the nozzle-openings 38 from said edge, the correct distance between these openings being maintained by the links 116. In this lateral movement the pawls 76 may share, turning about their pivots, and thus avoiding accidental release of the driver-rods 46, which they normally retain. The jack is elevated and the sole pressed against the abutment-surfaces 36 of the nozzles, the supports 26 yielding longitudinally of the drivers against the springs 30 to allow the nozzles to adapt themselves to irregularities of the surface. The bar 80, first rising, causes the release of the tensioned springs 72 by withdrawal of the pawls 76 from beneath the driver-retaining shoulders 75 under the influence of the contact-screws 106. The consequent descent of the drivers brings them against tacks T contained in the nozzle-quills 56, where they have been delivered at the proper time through the tubes 60 from the distributor D. The sharp stroke of the drivers, under the influence of the springs, effectively forces the tacks into the sole, and, near the termination of their movement, the engagement of the support-collars 32 by the driver-cushions 64 produces an additional pressure between the abutment-surfaces and the work, which gives the proper resistance to the clinching force. Downward movement of the bar 80, followed by its rise to the normal position after the drivers have thus functioned, causes the plate 78 to swing the lever-sections 130, 132 to reset the templet for the succeeding operation, said sections now being latched together at 142 and 144. That they should be in the correct relation for this latching, regardless of whether the operator

had continued depression of the treadle, is insured by the action of the cam 90 upon the bar 162 through the link 169. During the rise of the bar 80 and plate 78, the pawls 5 76 are in position to engage the driver shoulders 75, resetting the springs 72. The machine is now ready for another operation.

The application for Letters Patent for improvements in fastening-inserting apparatus filed in my name on December 23, 1926, and bearing the Serial No. 156,580 contains claims 10 applicable to the present invention.

Having described my invention, what I claim as new and desire to secure by Letters 15 Patent of the United States is:

1. In a shoe machine, a movable jack, a plurality of yieldable supports co-operating therewith, and a tool movable in each support, each of said supports being arranged 20 to yield longitudinally of the tool and transversely thereof by contact of the jacked work with the supports.

2. In a fastening-inserting machine, the combination with a frame, of a carrier movable on the frame, a support yieldable bodily through the carrier, and a fastening-driver movable in the support under the power of the machine.

3. The combination with a frame, of a carrier movable upon the frame to correspond to the work, a support yieldable with respect to the carrier under the influence of the work, a fastening-driver movable in the support, and actuating means for the driver mounted upon 35 the frame.

4. In a fastening-inserting machine, a frame, a sleeve pivoted thereon, a support yieldable through the sleeve, and a driver mounted to reciprocate in the support.

5. In a fastening-inserting machine, a frame, a carrier-sleeve, a universal joint connecting the sleeve to the frame, a support guided in the sleeve, a spring interposed between the sleeve and support, and a driver 55 mounted to reciprocate in the support.

6. In a fastening-inserting machine, a plurality of yieldable supports, a driver arranged to reciprocate in each support, a spring arranged to impart to each driver its inserting 60 movement, a member common to all the springs and to which they are secured, and members movable upon said common member and interposed between the springs and drivers.

55 7. In a fastening-inserting machine, a reciprocatory driver, a support for the driver arranged to both yield longitudinally of said driver under the influence of the work and to move laterally, a spring arranged to impart 65 to the driver its inserting movement, and means operated by the machine to tension the spring.

8. In a fastening-inserting machine, a frame, a support, a universal joint between 65 the frame and support, a driver arranged to

reciprocate in the support, a spring fixed to the frame, and actuating connections between the spring and driver arranged to permit universal movement of the support.

9. In a fastening-inserting machine, a frame, a support, a universal joint between the frame and support and through which said support is movable, a driver arranged to reciprocate in the support, an actuating spring, and a link interposed between the 75 spring and driver.

10. In a fastening-inserting machine, a frame, a support, a universal joint between the frame and support and through which said support is movable, a driver arranged to 80 reciprocate in the support, a lever fulcrumed upon the frame, a spring acting upon the lever, and a link connecting the lever and driver.

11. In a machine for inserting fastenings 35 in shoe bottoms, a jack, a plurality of supports surrounding the jack, a driver movable in each support, a series of springs situated outside the supports, there being a spring acting upon each driver and arranged to produce 40 the inserting stroke, a movable member acting upon the drivers to tension their springs simultaneously, and means for releasing the drivers from the member.

12. In a fastening-inserting machine, a 95 plurality of movable supports, a driver movable in each support, a spring acting upon each driver, a traveling pawl for engagement with each driver and being movable under the influence of the corresponding support, 100 and means for disengaging the pawls from the drivers.

13. In a fastening-inserting machine, a plurality of movable supports, a driver movable in each support, a spring acting upon each driver, a reciprocatory member, and a pawl for each driver movable upon the member under the influence of the support for said 105 driver.

14. In a fastening-inserting machine, a 110 plurality of supports, a driver movable in each support, a spring acting upon each driver, a reciprocatory member, a pawl pivoted upon the member for each driver and normally retaining said driver with its spring 115 under tension, a contact member into engagement with which each pawl is carried to release the driver, and means arranged to vary the normal relation between each contact member and its pawl.

15. In a fastening-inserting machine, a movable support having spaced walls, a driver mounted to reciprocate in the support and having a projection guided between the walls, a spring acting upon the driver, and a traveling member movable between the walls and engaging the driver-projection.

16. In a fastening-inserting machine, a movable support having spaced walls, a universal joint by which the support is carried,

- a driver mounted to reciprocate in the support and having a projection guided between the walls, a spring acting upon the driver, and a spring-tensioning member engaging 5 the driver-projection and arranged to limit the movement of the support upon its universal joint.
17. In a fastening-inserting machine, a frame, a support yieldable longitudinally and 10 laterally in the frame and provided at one extremity with an abutment-surface for the work and at the opposite extremity with a contact-surface, a driver mounted to reciprocate in and move with the support and having 15 a surface movable into engagement with the contact-surface of said support, and an actuating spring for the driver secured to the frame.
18. In a fastening-inserting machine, a reciprocating driver, and a support for the driver arranged to yield longitudinally of 20 said driver under the influence of the work and also to move laterally, there being surfaces upon the driver and support arranged 25 to contact and impart to said support a longitudinal movement toward the work.
19. In a fastening-inserting machine, a frame, a carrier movable thereon, a support having an abutment-surface and being movable 30 in the carrier, a spring interposed between the carrier and support and arranged to be compressed by engagement of the work with the abutment-surface, and a fastening-driver mounted to reciprocate in the support 35 and provided with a surface movable into contact with said support to permit the spring to elongate.
20. In a fastening-inserting machine, a frame, carriers movable thereon, supports respectively movable in the carriers and each 40 having an abutment-surface, a spring interposed between each carrier and its support and arranged to be compressed by engagement of the work with the abutment-surface, a fastening-driver mounted to reciprocate in each support and provided with a surface 45 movable into contact with said support, and a spring individual to each driver, said spring being secured to the frame and arranged to actuate its driver and effect said contact.
21. In a fastening-inserting machine, fastening-inserting sections movable independently of each other laterally toward and from 55 the work, and members connecting the sections, there being one of said members between each section and the adjacent section and arranged to determine the spacing of 60 said sections during their independent movement in both directions laterally.
22. In a fastening-inserting machine, fastening-inserting sections movable independently of each other, and links pivotally connecting each section to adjacent sections.
23. In a fastening-inserting machine, fas- 65 tening-inserting sections movable independently of each other, members connecting the sections and arranged to determine the spacing of said sections, and means acting upon the spacing members and tending to draw 70 the sections together.
24. In a fastening-inserting machine, a series of fastening-inserting sections movable independently of each other, links connecting the sections, and means for applying 75 tension to a terminal link of the series.
25. In a fastening-inserting machine, a series of fastening-inserting sections movable independently of each other, a series of links connecting the sections, and a spring 80 exerting its tension upon each terminal link.
26. In a fastening-inserting machine, a normally fixed fastening-inserting section, a series of movable sections at each side of the fixed section, and spacing members connecting the sections of each movable series to 85 each other and to the fixed section.
27. In a machine for securing the soles at the toe-portions of shoes, a fastening-inserting section arranged to operate at the end of 90 the toe and normally fixed against movement, a series of inserting sections which operate at each side of the toe, and means for drawing said series toward each other.
28. In a machine for securing the soles at the toe-portions of shoes, a fastening-inserting section arranged to operate at the end of 95 the toe and normally fixed against movement, a series of inserting sections which operate at each side of the toe, and links connecting the fixed section to the movable section at each side and said movable sections 100 successively to each other.
29. In a machine for securing the soles at the toe-portions of shoes, a fastening-inserting section arranged to operate at the end of 105 the toe and normally fixed against movement, a series of inserting sections which operate at each side of the toe, links connecting the fixed section to the movable section at each side and said movable sections successively to each other, and springs exerting their force 110 through the terminal links of both series.
30. In a fastening-inserting machine, a frame, a plurality of supports containing reciprocating drivers, universal joints connecting the supports to the frame, guiding means for the ends of the driver-supports opposite the universal joints and including converging slots and cooperating projections, and means for forcing the projections inwardly along the slots.
31. In a fastening-inserting machine, a frame, a plurality of supports containing reciprocating drivers, universal joints connecting the supports to the frame, guiding means for the ends of the driver-supports opposite the universal joints and including converging 115 slots and cooperating projections, links 120
- 125
- 130

- connecting the supports, and springs exerting their force upon the links.
32. In a shoe machine, a plurality of tool-supports arranged to yield outwardly from an operating position, and a member movable into contact with the supports to effect their outward movement.
33. In a shoe machine, a plurality of tool-supports arranged to yield outwardly from an operating position, and a member movable into contact with the supports to effect their outward movement and then movable oppositely to release the supports for the assumption of their operating position.
34. In a shoe machine, a plurality of tool-supports arranged to yield to conform to the contour of the work, and a member having a contour approximating that of the work and being movable to separate the supports.
35. In a shoe machine, a plurality of tool-supports arranged to yield to conform to the contour of the work, a member having a contour approximating that of the work, and means for moving the member in contact with the supports to carry them to points outside the work and for withdrawing said member to permit the supports to engage the work.
36. In a fastening-inserting machine, a plurality of inserting sections, a member corresponding in contour to the work receiving the fastenings and contacting with the sections, and means for moving said member to separate the sections.
37. In a fastening-inserting machine, a plurality of inserting sections, a templet co-operating with the sections, springs forcing the sections toward the templet, and means for moving the templet into and out of contact with the sections.
38. In a fastening-inserting machine, an inserting section, a positioning member into co-operation with which the section is urged, means acting in the operation of the machine for moving the positioning member into contact with the section, and operator-governed means for freeing the positioning member from the moving means.
39. In a fastening-inserting machine, an inserting section, a positioning member into co-operation with which the section is urged, means acting in the operation of the machine for moving the positioning member into contact with the section, and means controlled by the operator for starting the machine, said controlling means being also arranged to free the positioning member from the moving means.
40. In a fastening-inserting machine, a reciprocal actuating member, a yieldable inserting section, a lever movable by the actuating member, a templet carried by the lever and movable against the section under the influence of the actuating member, and an operator-governed member for releasing

the templet from the effect of the actuating member.

41. In a fastening-inserting machine, a reciprocal actuating member, a yieldable inserting section, a lever movable by the actuating member and having relatively movable arms, a templet carried by one of the arms and being movable against the inserting section under the influence of the actuating member upon the other arm, means for connecting the arms to compel them to move together, and means for freeing the templet-carrying arm from the connecting means.

42. In a fastening-inserting machine, a reciprocal actuating member, a yieldable inserting section, a lever movable by the actuating member and having relatively movable arms, a templet carried by one of the arms and being movable against the inserting section under the influence of the actuating member upon the other arm, means for connecting the arms to compel them to move together, and a treadle arranged to start the machine and to act upon the connecting means.

43. In a fastening-inserting machine, a reciprocal actuating member, a yieldable inserting section, a lever movable by the actuating member and having relatively movable arms, a templet carried by one of the arms and being movable against the inserting section under the influence of the actuating member upon the other arm, a latch pivoted upon one arm and engaging the other, a treadle arranged to start the machine, and a member movable by the treadle and arranged to disengage the latch.

44. In a fastening-inserting machine, an inserting section, a positioning member co-operating with the section, means for moving the positioning member into contact with the section, operator-governed means for freeing the positioning member from the moving means, and means for re-establishing the control of the positioning member by the moving means.

45. In a fastening-inserting machine, an inserting section, a positioning member into co-operation with which the section is urged, means acting in the operation of the machine for moving the positioning member into contact with the section, operator-governed means for freeing the positioning member from the moving means, and means for re-establishing the control of the positioning member by the moving means.

46. In a fastening-inserting machine, an inserting section, a positioning member into co-operation with which the section is urged, means acting in the operation of the machine for moving the positioning member into contact with the section, operator-governed means for freeing the positioning member from the moving means, and means movable under the power of the machine for re-establishing the control of the positioning member by the moving means.

lishing the control of the positioning member by the moving means.

47. In a fastening-inserting machine, a reciprocatory actuating member, a yieldable inserting section, a lever movable by the actuating member and having relatively movable arms, a templet carried by one of the arms and being movable against the inserting section under the influence of the actuating member upon the other arm, means for connecting the arms to compel them to move together, means for freeing the templet-carrying arm from the connecting means, and means for re-establishing connection between the arms.

48. In a fastening-inserting machine, a reciprocatory actuating member, a yieldable inserting section, a lever movable by the actuating member and having relatively movable arms, a templet carried by one of the arms and being movable against the inserting section under the influence of the actuating member upon the other arm, means for connecting the arms to compel them to move together, a treadle arranged to start the machine and release the connecting means, and means made effective in the operation of the machine for restoring connection between the arms.

49. In a fastening-inserting machine, a reciprocatory actuating member, a yieldable inserting section, a lever movable by the actuating member and having relatively movable arms, a templet carried by one of the arms and being movable against the inserting section under the influence of the actuating member upon the other arm, a latch pivoted upon one arm and engaging the other, a treadle arranged to start the machine, a member movable by the treadle and arranged to disengage the latch, and a member movable under the power of the machine and arranged to restore the engagement of the latch.

50. In a fastening-inserting machine, a plurality of inserting sections arranged to yield outwardly from an operating position, a movable member arranged to force out a plurality of the sections, and means independent of said member for moving a portion of such plural sections.

51. In a shoe machine, a work-support, a plurality of operating sections arranged to move toward and from the work-support, a member movable into contact with the sections to force them from the support, and means arranged to move a particular section from the support.

52. In a shoe machine, a work-support, a plurality of operating sections arranged to move toward and from the work-support, a member movable under the power of the machine into contact with the sections to force them from the support, and means arranged

for manipulation by the operator to move a particular section from the support.

53. In a shoe machine, a plurality of operating sections, springs arranged to move the sections toward an operating position, means operating under the power of the machine for forcing back the sections against the springs, and operator-controlled means arranged to force back a portion of the sections.

54. In a fastening-inserting machine, a plurality of inserting sections extending on opposite sides of the work, levers connected to the sections and arranged to move them toward and from said work, and means arranged to move said levers simultaneously, and means arranged to secure against movement the levers as they are thus adjusted.

55. In a fastening-inserting machine, a plurality of yieldable inserting sections having projections, levers provided with slots receiving the projections and allowing the sections to yield in the direction of elongation of the slots, and means for connecting the levers to move together.

56. In a fastening-inserting machine, a plurality of inserting sections, levers connected to the sections, one of said levers having an arm, gearing connecting the levers, and clamping means associated with the lever-arm.

57. In a fastening-inserting machine, inserting mechanism, actuating mechanism for the inserting mechanism, a movable work-gage associated with the inserting mechanism, operator-governed means for controlling the actuating mechanism, and a lock for said operator-governed means controlled by the gage.

58. In a fastening-inserting machine, inserting mechanism, a support movable to carry the work to inserting position, a movable back stop for the work, actuating mechanism for the inserting mechanism, starting connections for the actuating mechanism, and a locking slide movable by the back stop and acting upon the connections.

59. In a fastening-inserting machine, inserting mechanism, a support movable to carry the work to inserting position, actuating mechanism for the inserting mechanism, starting connections for the actuating mechanism, a locking member for the connections, a back stop for the work yieldable upon the locking member, and a spring arranged to act upon both the locking member and the back stop.

60. In a fastening-inserting machine, inserting mechanism, a support movable to carry the work to inserting position, actuating mechanism for the inserting mechanism, starting connections for the actuating mechanism, a locking slide for the connections, a back stop pivoted upon the slide, and a spring arranged to move the slide to locking position.

and to maintain the back stop in its normal relation.

61. In a machine for securing soles at the toe-portions of shoes, a plurality of fastening-inserting sections arranged in close proximity to one another in a series to co-operate with the toe of a shoe, each of said sections having a nozzle for engagement with the bottom of a sole and a gage for contact with the sole-edge, and a mounting for each section arranged to allow the sections to yield independently to conform to the contour of both the bottom and periphery of the sole.

62. In a machine for securing soles at the toe-portions of shoes, a frame, a plurality of fastening-inserting sections arranged in close proximity to one another in a series to co-operate with the toe of a shoe, each of said sections having a nozzle for engagement with the bottom of a sole and a gage for contact with the sole-edge, a mounting for each section arranged to allow the sections to yield upon the frame independently to conform to the contour of both the bottom and periphery of the sole, a series of springs secured to the frame outside the sections, each spring co-operating with a corresponding section and permitting its conforming movements, and means movable by the machine in its operation for energizing the springs.

63. In a machine for securing soles at the toe-portions of shoes, a frame, a plurality of fastening-inserting sections arranged in close proximity to one another in a series to co-operate with the toe of a shoe, each of said sections having a nozzle for engagement with the bottom of a sole, a gage for contact with the sole-edge and a driver movable through the nozzle, a mounting for each section arranged to allow the sections to yield upon the frame independently to conform to the contour of both the bottom and periphery of the sole, a series of springs secured to the frame outside the sections, each spring acting upon the driver of a corresponding section and permitting the conforming movements of said section, each driver under the influence of its spring contacting with the body of its section to force the nozzle against the sole-bottom, and means movable by the machine in its operation for energizing the springs.

64. In a machine for securing soles at the toe-portions of shoes, a plurality of fastening-inserting sections arranged in close proximity to one another in a series to co-operate with the toe of a shoe, each of said sections having a nozzle for engagement with the bottom of a sole and a gage for contact with the sole-edge, a mounting for each section arranged to allow the sections to yield independently to conform to the contour of both the bottom and periphery of the sole, and

spacing members connecting respective pairs of adjacent sections.

In testimony whereof I have signed my name to this specification.
